UNITED STATES PATENT OFFICE.

HEINRICH KAISER, OF HILDEN, GERMANY.

CHILD'S PISTOL.

SPECIFICATION forming part of Letters Patent No. 787,844, dated April 18, 1905.

Application filed December 1, 1904. Serial No. 235,051.

To all whom it may concern:

Be it known that I, HEINRICH KAISER, manufacturer, of Hilden, Rhineland, in the German Empire, have invented a new and useful 5 Child's Pistol, of which the following is a specification.

My invention relates to improvements in children's pistols in which a stopper is pressed into the end of the pistol-barrel, which then o can be shot out by air-pressure.

My improvements essentially consist therein that the air-pressure piston which is actuated directly by the trigger is tightened in its chamber by a rubber pipe. The one end of 5 the latter is fastened to the piston and the other to the chamber-wall. By this arrangement the piston has a slight range of motion. It is pressed back automatically by a spring. The pistol-trigger forms a lever one arm of 10 which moves the piston, while the other projects outward and serves as the trigger proper.

The object of my invention is illustrated by the accompanying drawings, in which—

25 Figure 1 shows the pistol in vertical section, its piston being in rest. Fig. 2 shows the same section, but the piston being in actuation.

The pistol essentially consists of the handle 30 a, the piston b, the trigger c, the piston-chamber d, and the barrel e. The piston-chamber is formed by a cylinder of large diameter. The same is fastened to the handle a by a drum f. The piston b is guided within the 35 chamber. The piston is in connection with the chamber by a rubber pipe g. At the foremost end of the piston a groove is provided around its circumference and a projecting shoulder is arranged in the piston-chamber d. The rubber pipe g is fastened to the chamber-wall and the piston by wire wound around the ends of the same at the points of attachment. The piston b is provided at the 40 trigger end with a central projection h, which passes through the wall of the drum f. Within the handle a of the pistol a lever c is pivoted. The end extending outward serves 45 as trigger and the other end works against the projection h. A spring i is inserted be-

tween the front side of the piston b and the 50 chamber-wall. This presses the piston against the opposite wall of the chamber d.

In use the barrel e is closed by a stopper k. When now the trigger is strongly drawn back, the piston is thereby moved forward and the 55 air within the chamber d is compressed, whereby the stopper k will be pushed out and a detonation will be caused.

Having now described the nature of my invention, what I claim is—

1. In a child's pistol the combination of 60 a handle, an air-chamber fastened to the same, a barrel extending from the front side of the air-chamber, a piston guided within the latter, a rubber pipe one end of which is fastened to the air-chamber and the other end to the piston, a spring pushing the piston back and a trigger pivoted in the handle which actuates the piston, as and for the purpose specified.

2. In a child's pistol the combination of 65 a handle, a cylindrical drum fastened to the same, an air-chamber arranged within said drum, a barrel extending from the front side of the air-chamber, a piston guided within the latter, a rubber pipe one end of which is fastened to the air-chamber and the other end to the piston, a spring pushing the piston back and a trigger pivoted in the handle which 70 actuates the piston, as and for the purpose specified.

3. In a child's pistol the combination of 75 a handle, a cylindrical drum fastened to the same, an air-chamber arranged within said drum, a barrel extending from the front side of the air-chamber, a piston guided within the latter, a rubber pipe one end of which is fastened to the air-chamber and the other end to the piston, a spring pushing the piston back and a lever pivoted in the handle one end 80 of which actuates the piston and the other end extending outward serves as trigger, as and for the purpose specified.

HEINRICH KAISER.
